(74) Attorney, Agent, or Firm — Hodgson Russ LLP

(57) **CLAIM**

The ornamental design for a workstation for handling goods, as shown and described.

DESCRIPTION

2. Workstation for handling goods

2.1: Front elevation view

2.2: Back elevation view

2.3: Left elevation view

2.4: Right elevation view

2.5: Top plan view

2.6: Perspective view

The workstation for handling goods is used for at least one of the following operations: sorting, picking, catching, placing, storing or position changing of containers, replenishing goods, putting goods on/off shelves, tallying goods, or making an inventory etc.; and the bottom view of design 2 is omitted since it is not often seen.

1 Claim, 6 Drawing Sheets
